ORNATE GAS LAMP

Bernard Bernstein, 6029 N. 16th Drive,
Phoenix, Ariz. 85016

Filed Sept. 29, 1966, Ser. No. 4,081

Term of patent 3½ years

(Cl. D48—31)

fig. 1

fig. 2

FIG. 1 is a perspective view of the ornate gas lamp of the invention generally showing the details and features of the bottom of the lamp and the bottom and side surfaces of the various structural elements.

FIG. 2 is a perspective view of the ornate gas lamp of the invention showing generally the top of the lamp and the top and side surfaces of the various elements of the lamp.

The broken line showing of a support post in the figures is for illustrative purposes only.

I claim:

The ornamental design for an ornate gas lamp, as shown and described.
